UNITED STATES PATENT OFFICE.

BENJAMIN R. VARLEY, OF JERSEY CITY, NEW JERSEY, ASSIGNOR TO VARLEY DUPLEX MAGNET COMPANY, OF JERSEY CITY, NEW JERSEY, A CORPORATION OF NEW JERSEY.

WINDING-MACHINE.

1,102,369.

Specification of Letters Patent.

Patented July 7, 1914.

Application filed October 5, 1912. Serial No. 724,018.

To all whom it may concern:

Be it known that I, BENJAMIN R. VARLEY, a citizen of the United States, residing at Jersey City, in the county of Hudson and State of New Jersey, have invented certain new and useful Improvements in Winding-Machines, of which the following is a specification.

My invention relates broadly and generally to new and useful improvements in winding machines, and more particularly machines for winding wire in coil form to form electro-magnets for use in the electrical arts, for instance the field magnets of motors and dynamos.

The object of the invention is to provide in combination with a winding spindle or mandrel upon which the coil is laid, means whereby binding or tying bands or threads may be laid between the layers of the coil while the latter is being wound so as to secure the layers and turns, particularly the outside turn of the layers, so that the turns may be held against dislodgment when the winding is removed from the mandrel.

The invention consists in the construction of parts and their aggroupment in operative combination to be more fully described hereinafter, and the novelty of which will be particularly pointed out and distinctly claimed.

I have fully and clearly illustrated my invention in the accompanying drawings to be taken as a part of this specification, and wherein,

Figure 1 is a view in side elevation of a structure embodying my invention; Fig. 2 is a view in side elevation, partly in section, showing the parts in another position from that shown in Fig. 1; Fig. 3 is a section on the line 3-3 of Fig. 1; Fig. 4 is a detail sectional view on the line 4-4 of Fig. 3; Fig. 5 is a view in side elevation of an embodiment of the invention showing the parts in an intermediate position of those shown in Figs. 1 and 2; Fig. 6 is a top plan view showing arrangement of two of the elements; Fig. 7 is a longitudinal section through a part of a mandrel showing in section a part of a winding thereon, and the manner in which the binding strip or thread is applied thereto.

Referring to the drawings by characters of reference, 1 designates a winding shaft or spindle adapted to be driven in any suitable manner, and 2 is a mandrel mounted on and adapted to rotate with the spindle, said mandrel being shown as polysided, and having grooved corner-pieces 3 for guiding the turns of the first layer of a winding. 55 The mandrel is also provided with end flanges or heads 4, 5 abutting the ends of the body of the mandrel and having their inner faces parallel to each other and, at right angles to the longitudinal axis of the 60 mandrel. The spindle has bearing in one of the frame members 1^a of a winding machine. Mounted on the spindle adjacent the outer face of each of the heads 4, 5 are circular plates 6, 7 respectively, lying in parallel planes at right angles to the axis of rotation of the mandrel. The plates are mounted in any suitable manner so as to rotate with the spindle, the inner plate 6 abutting a shoulder 8 on the spindle 1 and having a pin or pins 9 adapted to enter a socket 10 in the flange or head 4, while the plate 7 is provided with a pin 11 to enter a socket 12 in the flange or head 5, a nut 13 threaded onto the outer end of the spindle serving to 70 move the mandrel body, the flange plates 4, 5, and the plates 6, 7 toward the shoulder 8, and clamp them against the shoulder so that all of the parts mentioned are rigidly secured together to rotate with the spindle. 75

The nut 14 is threaded on the end of a screw 14^a which is connected to the mandrel body 2 by means not shown, to draw said body toward the plate 5 and thereby expand the mandrel. The construction of 90 the collapsible mandrel and the corner pieces are not of themselves my invention, but I have employed the same as showing a type of mandrel to which my invention, as hereinafter claimed, is applicable, although I 95 desire it to be understood that I do not limit myself to the particular type of mandrel shown and described.

The flange plates 6, 7 are each provided with a circumferential lateral flange 15 extending toward the mandrel, and the inner edge of each flange is provided with inwardly projecting projections 16, preferably spaced equally from each other, around the

flanges, the projections on flange 15 of one plate being opposite those on the flange of the other plate. Each of the projections 16 is chamfered at its inner end as at 16* to provide an inclined engaging face for a purpose to be presently set forth. Extending from the frame member 1* or other suitable support, is a guide bar 17, extending parallel to the spindle 1, upon which bar is 10 slidably mounted a sleeve 18, carrying an annular element 19, arranged concentric with the longitudinal axis of the mandrel spindle 1, and of an interior diameter greater than the outside diameter of the plates 6, 7, so that said element may be passed over said plates. A bar 20, also projecting from the frame 1* or other support, is arranged parallel to the bar 17, and is engaged by a split, or half-sleeve 21, so that said element 19 will 20 always be moved in a straight line lengthwise of the spindle 1, and will be held against movement laterally of the spindle. The element 19 at the part toward the outer end of the spindle 1 is provided with an inner 25 rabbet 22, closed at its side by a ring-piece 23 secured to the face of the element 19 by means of screws 24, so that the element 19 is provided with an annular groove on its inner face. Arranged inside the element 19, 30 which may be termed a shifting element, is arranged a strand supply supporting means consisting of a ring member 25 concentric with said element 19, the plates 6, 7 and the mandrel, and of an outside diameter less 35 than the distance between two projections 16 opposite to each other on one of the flanges 15, and less than the inside diameter of said flanges 15, so that said member 25 may be received inside the flange of said plates 6, 7. 40 The member 25 is provided with a plurality of radially extending projections 26, of a width substantially equal to the spaces between the projections 16, and spaced apart from each other a distance substantially 45 equal to the width of said projections 16. The projections 26 extend into the annular groove in the inside of the element 19, so that the member 25 is movable with the element 19, and is freely rotatable relative to 50 the same and the mandrel.

The arrangement of the projections 16, on the plates 6 and 7, and the projections 26 on the member 25, is such that when the element 19 is moved to place the member 25 within the flange of either of said plates, the projections 16, and 26, will interlock so that the member 25 will rotate with the plate 6 or 7 which it engages. The chamfered ends of the projections 16 engage the rim of the member 25 so as to center said member when it is moved into engagement with one of the plates, and facilitates such engagement, the flange 15 and the projections 16 thereon extending between the member 25 and the element 19 when the parts are engaged. It will

be seen that the plates 6 and 7 constitute means for clutching the member 25 to the opposite ends of the mandrel, and while I have shown the projections 16, 26 as the means for establishing the clutch engagement, I desire it understood that I do not limit myself to the particular means shown and described as other means of engagement may be employed, although the one disclosed is preferable.

Mounted inside the member 25 are a plurality of supply devices for the bands or strands, the same preferably consisting of flanged spools 27 journaled in inwardly projecting ears 28 on the inner side of the member 25, said spools having their axes of rotation arranged circumferentially of the member 25, at right angles to the axes of rotation of the mandrel. I do not limit myself to the particular number of these devices, as there may be more or less than the number shown without departing from the intended spirit and scope of this invention.

The members 19 and 25 are split in their peripheries to provide passages as shown at 29, 30 respectively so that when they are moved lengthwise of the mandrel during the winding operation on the mandrel, the strand leading to the mandrel from the supply does not have to be disconnected, but 5 may pass through said passages.

The operation of the above described embodiment of the invention is as follows: The strand α to be wound is led from a suitable guide wheel y , and is secured to the mandrel adjacent one of the heads, say the head 4 as shown in Fig. 1, and a turn of the strand α is laid on the mandrel. The tie bands 31 from the spools 27 are then secured to the first turn, preferably a number of strands 105 from adjacent spools being secured at one point to said turn, as shown in Figs. 1, 2 and 3, the member 25 being clutched to the mandrel at the end adjacent the first turn of the initial layer. The mandrel is then rotated, the plate 6 and the member 25 rotating with it, until a number of turns of the first layer have been completed, when the mandrel is stopped and the member 19 with the member 25 shifted toward the opposite 115 end of the mandrel, the strand α passing through the passages 29, 30. It will be understood that the mandrel is stopped in such position that the passages 29, 30 will be in alinement with each other, and with the 120 strand α leading to the mandrel. The member 19 is moved toward the end plate until the member 25 passes inside the flange 15 and the projections 16, 26 interlock, which movement serves to carry the binding 125 threads or bands across the turns of the layer which have been made on the mandrel, as shown in Fig. 2 of the drawings. The mandrel is then rotated again to lay the remainder of the layer already started, the 130

turns now being laid on top of the tie bands or threads so that the latter are bound down onto the surface of the mandrel, as shown in Fig. 7, the winding being continued until 5 the layer is completed and a part of the turns of the next superposed layer has been laid. The mandrel is then again stopped, with the openings 29, 30 in register, and alining with the strand α , and the member 10 19 is shifted toward the opposite clutch plate or member, which carries the binding bands or threads around the finishing or outside turn of the first layer and the starting or outside turn of the second layer. The 15 ring 25 being clutched to said opposite clutch plate, the mandrel is rotated to complete the second layer, the finishing turns being laid on top of the binding bands, the next (or third) layer being started, and the bands 20 carried around the adjacent outer turns of the second and third layers, the procedure described being repeated as desired throughout the winding at whatever turns or layers it may be desired to fasten in with the binding bands or threads.

What I claim and desire to secure by Letters Patent of the United States is,

1. In combination, a winding mandrel, and means movable lengthwise of the mandrel and rotatable therewith for laying a tie band lengthwise of the mandrel over a layer of a winding on the mandrel.

2. In combination, a winding mandrel, means movable lengthwise of the mandrel 35 for laying a tie band lengthwise of the mandrel over a layer of a winding on the mandrel, and means for causing rotation of said means with the mandrel.

3. In combination, a winding mandrel, 40 means movable lengthwise of the mandrel for laying a tie band lengthwise of the mandrel over a layer of a winding on the mandrel, and means for connecting the said means alternately with the opposite ends of 45 the mandrel to rotate therewith.

4. In combination, a winding mandrel, a support movable lengthwise of the mandrel, a tie band supply carried by said support, and means for clutching said supply alter- 50 nately to opposite ends of the mandrel.

5. In combination, a winding mandrel, a support movable lengthwise of the mandrel, a plurality of spools rotatably mounted on 55 said support, and means for clutching said spools to the mandrel.

6. In combination, a winding mandrel, a non-rotatable support movable lengthwise of the mandrel, and a spool support rotatably mounted on and supported by said first 60 named support and movable therewith, and carrying a plurality of spools surrounding the mandrel.

7. In combination, a winding mandrel, a non-rotatable support movable lengthwise of 65 the mandrel, a spool support rotatably

mounted on said first named support and movable therewith, and carrying a plurality of spools surrounding the mandrel, and means for connecting the spool support to the mandrel to rotate therewith.

8. In combination, a winding mandrel, a non-rotatable support movable lengthwise of the mandrel, a spool support rotatably mounted on said first named support and movable therewith, and carrying a plurality of spools surrounding the mandrel, and means at the opposite ends of the mandrel for connecting the spool support to the mandrel to rotate therewith.

9. In combination, a winding mandrel, a non-rotatable support movable lengthwise of the mandrel, a ring member rotatable on said support and movable therewith, and a plurality of spools on the ring member surrounding the mandrel, and means for rotat- 85 ing said ring member.

10. In combination, a winding mandrel, a support movable lengthwise of the mandrel, a ring member rotatable on said support and movable therewith, a plurality of spools on the ring member surrounding the mandrel, and means for connecting the ring member to the mandrel to rotate therewith.

11. In combination, a winding mandrel, a support, a plurality of spools on said sup- 95 port and surrounding said mandrel, means whereby said spools are rotatable with the mandrel, and means for moving said spools lengthwise of the mandrel.

12. In combination, a winding mandrel, a 100 plurality of spool supports surrounding the mandrel, means for moving said spool supports lengthwise of the mandrel, and means for connecting said spool supports alternately with the opposite ends of the man- drel.

13. In combination, a winding mandrel, clutch plates at the ends of the mandrel, a plurality of spool supports surrounding the mandrel, a rotatable support for said spool 110 supports, and means for moving the rotatable support lengthwise of the mandrel to connect it with one of the clutch plates.

14. In combination, a winding mandrel, clutch plates at the ends of the mandrel, a 115 plurality of spools surrounding the mandrel, a rotatable support for said spools, means for moving the support lengthwise of the mandrel, and means on the clutch plates and support to interlock to connect the said 120 plates and support.

15. In combination, a winding mandrel, a support, a spool on said support movable lengthwise of the mandrel, and means for connecting the spool to the mandrel to ro- 125 late therewith.

16. In combination, a winding mandrel, an annular support movable lengthwise of the mandrel, a ring member rotatable on said support and movable therewith, said 130

support and member being concentric with the mandrel, clutch-plates at the ends of the mandrel and rotatable therewith, and adapted to connect the ring member to the 5 mandrel to rotate therewith, and spool supports carried by the ring member and surrounding the mandrel.

17. In combination, a winding mandrel, an annular support movable lengthwise of 10 the mandrel, a ring member rotatable on said support and movable therewith, said support and member being concentric with the mandrel, clutch-plates at the ends of the mandrel and rotatable therewith, and 15 adapted to connect the ring member to the mandrel to rotate therewith, and spool supports carried by the ring member and surrounding the mandrel, said support and ring member having provision for the passage 20 of the strand being wound on the mandrel therethrough.

18. In combination, a winding mandrel, clutch members having spaced projections, at the ends of the mandrel, said members 25 being rotatable with the mandrel, an annular spool support movable lengthwise of the mandrel and surrounding the same, and having projections to coöperate with those on the clutch-plates to lock the said support 30 to the mandrel to rotate therewith.

19. In combination, a winding mandrel, clutch members at the ends of the mandrel and having spaced projections, said members being rotatable with the mandrel, an 35 annular member surrounding the mandrel and movable lengthwise thereof, and having an internal circumferential groove, an annular member rotatable inside the first-named annular member and carrying a plurality of spool supports, and having a plurality of projections extending into said groove, said projections being movable with the first member into engagement with the projections on the clutch members to connect the second annular member to the mandrel.

20. In combination, a winding mandrel, a plurality of spools surrounding the mandrel, means for moving said spools lengthwise of 50 the mandrel, and means for connecting said

spools alternately with the opposite ends of the mandrel.

21. In combination, a winding mandrel, clutch-plates at the ends of the mandrel, a plurality of spools surrounding the mandrel, 55 a rotatable support for said spools, and means for moving the rotatable support lengthwise of the mandrel to connect it with one of the clutch plates.

22. In combination, a winding mandrel, 60 clutch members at the ends of the mandrel and having spaced projections, said members being rotatable with the mandrel, an annular member surrounding the mandrel and movable lengthwise thereof and having 65 an internal circumferential groove, a guide rod upon which said annular member is mounted, an annular member rotatable inside the first-named annular member and carrying a plurality of spool supports, and 70 having a plurality of projections extending into said groove, said projections being movable with the first member into engagement with the projections on the clutch members to connect the second annular 75 member to the mandrel.

23. In combination, a winding mandrel, clutch members at the ends of the mandrel and having spaced projections, said members being rotatable with the mandrel, an 80 annular member surrounding the mandrel, and movable lengthwise thereof and having an internal circumferential groove, a pair of guide rods upon which said annular member is mounted, an annular member rotatable inside the first-named annular member and carrying a plurality of spool supports, and having a plurality of projections extending into said groove, said projections being movable with the first member into 85 engagement with the projections on the clutch members to connect the second annular member to the mandrel.

In testimony whereof I have hereunto signed my name in the presence of two sub- 90 scribing witnesses.

BENJAMIN R. VARLEY.
